UNITED STATES PATENT OFFICE.

PETER HARDMAN, OF WILLIMANTIC, CONNECTICUT.

SPOOL.

No. 875,993.

Specification of Letters Patent.

Patented Jan. 7, 1908.

Application filed February 20, 1907. Serial No. 358,361.

To all whom it may concern:

Be it known that PETER HARDMAN, a citizen of the United States, residing at Willimantic, Windham county, Connecticut, has invented certain new and useful Improvements in Spools, of which the following is a full, clear, and exact description.

My invention relates to improvements in spools for thread and the like, and the object 10 is to provide a simple, inexpensive and light weight article of that type, the same when completed possessing great strength and durability, the head portion thereof being so constructed as to effectively resist endwise 15 strains caused by the thread upon the spool.

In the accompanying drawings Figure 1 is a longitudinal sectional view of the completed article. Fig. 2 is an end elevation of the same. Fig. 3 is a detail of the securing 20 means for the heads. Fig. 4 is a plan view of a strip of paper from which the wedges are formed.

The body or cylindrical portion of the spool is designated by the numeral 1, and is 25 preferably formed of a strip of paper wound upon itself to form a series of laminations which may be cemented together (by glue, for instance) and which collectively constitute a tube of sufficient thickness to give the 30 necessary strength.

22 are the heads preferably formed of pulp, in accordance with my prior patent No. 843,454, of February 5, 1907, and of the usual shape, provided with a central tapered 35 opening 2^a.

33 are annular wedge members preferably formed of a tapered strip of paper 3^a wound upon itself to form a series of overlapping laminations which, like the spool body, may 40 be cemented or glued together, and are of such size as to snugly fit the spool body. After forming the wedges as set forth, each is slit vertically, as at 3^b, to allow the wedge to be expanded or contracted.

45 The heads are placed on the spool body near the center. The wedges 33 are secured to the extremities of the body by cement or glue or any other well known means. Their overlapping outer surfaces are covered with 50 a coat of some adhesive medium and the

heads moved outward, so that their tapered interiors ride upon the split wedges, which will begin to close, caused by the pressure from the inside walls of the heads, thus tightening the wedge 3 upon the body. The 55 spaces formed between the serrated surfaces of the wedges and the tapered portion of the heads form pockets for the adhesive medium, guaranteeing the presence of a sufficient quantity thereof, being held on the surface of the wedge as the head is moved outward to engage the same.

Any outward strain upon the head portions will only cause them to bind the wedges and thereby become more firmly united to 60 the body portion.

What I claim is:

1. In a spool, a hollow body portion, a separate head portion therefor, and means for uniting said head and body portions comprising 70 an annular wedge member secured to the outer side of the body portion and entering between said head and body portions.

2. In a spool, a hollow body portion, a separate head portion therefor, and means for uniting said head and body portions comprising 75 an annular wedge member secured to the said body portion and entering within said head portion one surface thereof being serrated.

3. In a spool, a hollow body, a separate head portion therefor, and means for uniting said head portion and body comprising an annular split wedge member provided with a 80 serrated outer surface secured to said body and engaging said head portion.

4. In a spool, a body portion, a separate head portion therefor, and means for uniting said head and body portions comprising a laminated split wedge portion secured to said 90 body portion and engaging said head portion.

5. In a spool, a body portion, a separate head portion provided with a central tapered aperture, a laminated split wedge member secured to said body portion engaging in said 95 tapered portion of the head to unite said head and body portions.

6. In a spool, a body portion, a separate head portion provided with a central tapered aperture, an annular laminated split wedge 100

member secured to said body portion and engaging said head portion, said wedge member having a serrated surface.

7. In a spool, a body portion, a separate head portion, an annular wedge member secured to the body portion consisting of a tapered strip bound upon itself to form the

tapered annular wedge uniting said head and body portions.

PETER HARDMAN.
